COLLAR SUPPORT

Albert P. Herrlinger, Cincinnati, Ohio, assignor
to The Herrlinger Paper Co., Cincinnati, Ohio,
a corporation of Ohio

Application December 19, 1932, Serial No. 647,856

1 Claim. (Cl. 223—83)

My invention relates to a new and improved collar support and more particularly to a support to be used in conjunction with shirts having attached collars, for the purpose of supporting the attached collar after the shirt has been laundered to prevent crushing of the collar when a plurality of shirts are bundled together.

The object of my invention is to provide a collar support having a body portion and a head portion connected together by means of a neck whereby the support can be folded for insertion of the head tabs under the wings of the collar and the body portion placed inside the collar band. A further object of my invention is to provide the body portion with extending edges which protrude above the edge of the collar when the support is positioned in the collar to protect the upper edges of the collar and prevent other objects from rubbing on the collar band which might tend to soil the band. A further object is to provide the ends of the head portion of the collar support with cutaway portions to present a pointed end to the head member whereby said ends will more securely grip the collar for holding the collar support in place. A further object is to provide cutaway portions in the body portion adjacent to the neck to provide a weakened portion in the neck whereby said neck will bend along a line parallel to the base of said cutaway portions for presenting upwardly extending edges on the body portion when the support is folded.

My invention will be further readily understood from the following description and claim and from the drawing, in which latter:

Fig. 1 is a perspective view looking at the front of a shirt and showing my improved collar support in position.

Fig. 2 is a cross-section of the same taken in the plane of the line 2—2 of Fig. 1, and

Fig. 3 is a plan view of my improved collar support.

It is customary for laundries after they have laundered shirts provided with attached collars to place in such collar a support to prevent crushing of the collar when a plurality of shirts and other articles are bundled together for delivery to the customer.

I have devised a new and improved collar support which not only supports the collar but also protects the upper edge of the collar and is very

easily inserted in the collar. This improved collar support consists of a sheet of material having sufficient flexibility to permit longitudinal flexing and comprises a body portion 11 provided with an arcuate edge 12 whereby the support, when positioned in a collar of a shirt, the edge 12 will rest on the back of the shirt. A head 13 is connected to the body portion by means of a neck 14 which extends into the body portion and has cutaway portions or incisions 15 in the body portion adjacent to the neck. The head and body portion are separated by arcuate incisions 16 extending from the cutaway portions 15 to the outer ends of the respective head and body portions. The ends 17 of the head portion are cut back as 15 at 18 to the incision 16 to present points 19 at the respective ends of the head portions for engaging the flaps of the collar 20 of the shirt 21.

When the collar support is positioned in the collar of a shirt the body portion 11 is placed within the inner face of the collar 20 and the head 13 is bent forward causing the neck to fold along a line adjacent the base of the incisions 15 within the body 11, for presenting upstanding edges 22 to the body portion which will project above the upper edge 23 of the collar 20 for protecting the upper edge of the collar. The head 13 being bent forward permits insertion of the respective ends 17 under the collar flaps for locking the collar support in position and firmly supporting the collar and preventing crushing of the collar when other objects are placed thereabove. The neck portion 14 when bent forward assumes a position between the joining ends of the collar proper.

Having thus fully described my invention what I claim as new and desire to secure by Letters Patent, is:

In combination with a shirt having a collar attached, a collar support comprising a flat flexible body portion arranged within the inner face 40 of said collar, a head adapted to be received under the collar flaps, said body portion being connected to said head and having central spaced apart incisions for forming a neck between said head and body portion, said neck folded along a line between the bases of said incisions within said body with the upper edge of said body portion projecting above said neck and head and the upper edge of said collar.

ALBERT P. HERRLINGER. 50
